UNITED STATES PATENT OFFICE

146,096

DESIGN FOR A CLASS PIN

Richard W. Bates, Annapolis, Md., assignor to
the 1948 A and B Classes of the United States
Naval Academy

Application March 16, 1946, Serial No. 127,574

Term of patent 3½ years

(Cl. D45—19)

To all whom it may concern:

Be it known that Richard W. Bates, a citizen
of the United States, residing at Annapolis, in
the county of Anne Arundel and State of Mary-
land, has invented a new, original, and ornamen-
tal Design for a Class Pin, of which the follow-
ing is a specification, reference being had to the
accompanying drawing, forming a part thereof.

In the drawing:

Fig. 1 is a front elevational view of a class pin
embodying my new design; and
Fig. 2 is a top plan view thereof.

I claim:

The ornamental design for a class pin, substan-
tially as shown.

RICHARD W. BATES.
